UNITED STATES PATENT OFFICE.

ZAIDA B. WEBB, OF MADISON, NEW JERSEY, ASSIGNOR TO WEBB FOLDING BOX COMPANY, OF NEWARK, NEW JERSEY, A CORPORATION OF NEW JERSEY.

FOLDING BOX.

SPECIFICATION forming part of Letters Patent No. 727,722, dated May 12, 1903.

Application filed March 18, 1902. Serial No. 98,771. (No model.)

To all whom it may concern:

Be it known that I, ZAIDA B. WEBB, of Madison, county of Morris, State of New Jersey, have invented certain new and useful 5 Improvements in Folding Boxes, of which the following is a full, clear, and exact description.

My invention relates to improvements in folding boxes; and the object of my invention is to produce a strong, simple, and attractive package which can be instantly set up or knocked down, which cuts to particularly good advantage, and which is adapted to form a box of the shape of a cube, although 15 this shape can be departed from. The box forming my invention is particularly intended to be very strong when set up and to be fastened or unfastened very quickly.

With these ends in view my invention consists of a folding box, the construction and arrangement of which will be hereinafter fully described and claimed.

Reference is to be had to the accompanying drawings, forming part of this specification, 25 in which similar figures of reference refer to similar parts throughout the several views.

Figure 1 is a detail of the box-blank. Fig. 2 is a perspective view of the partially-formed box; and Fig. 3 is a plan view of the box 30 when partially formed and flattened down for shipment, so as to be ready for use.

The box is made, preferably, though not necessarily, with its sides, top, and bottom of equal size, and it comprises a side 10 of rectangular shape, from two edges of which project two other side pieces 11 of the same size as the first-mentioned side piece, while the fourth side is formed by the two engaging wings 13, the several side pieces being preferably separated from each other by score-lines, and score-lines are preferably made wherever a bend occurs in the box. The two side pieces 11 are preferably provided with flaps 12, which are arranged at opposite edges 40 and are adapted to fold inward to form the box ends or top and bottom, as the case may be. The wings 13 are cut into, as shown at 45 14, the cut being preferably triangular, with the greater incline next the side pieces 11, 50 and the cut on one wing 13 is on the opposite

edge to that of the second wing, so that by these cuts engaging and slightly undercut tongues 15 are formed, one being relieved slightly by preference, as shown at 15°, so that the parts may be more easily engaged. 55 This, however, is not absolutely essential. The wings 13 have each a flap 16 of a size corresponding to one of the parts 10 or 11, which is adapted to fold inward to form the box-closure, and each extension or flap 16 60 has a terminal tuck 17 to be tucked into the box, so as to fasten the said parts 16. It will be seen, therefore, that to form the box it is only necessary to grasp the blank by the two opposite ends and bring the parts 13 together, 65 the blank being slightly twisted and the slots 14 pushed together, so that the tongues 15 will engage each other, lying on the inside of the parts 13, as shown in Fig. 2. Thus a very secure fastening is made, and it will be seen that 70 it can be very quickly accomplished.

To provide for quickly using the box or for shipping it ready for use, the above-mentioned parts can be fastened as described and as shown in Figs. 2 and 3, and then by pressing 75 on one side of the blank and with a little lateral motion the blank can be flattened down, as shown in Fig. 3. Then when the box is to be used it is only necessary to press it up to the shape shown in Fig. 2, turn in one set of 80 flaps 12, fold the extension or flap 16 over these flaps 12, tuck in the tuck 17, then fill the box, fold in the second flaps 12, turn the second flap 16 over them, and insert the tuck 17 in the box edge. The box may be provided with the cut-away portions terminating 85 nearer to or at the seam of the juncture of the wings and side pieces to make a joint that will leave the panels clear of edges to facilitate printing thereon, &c. Thus it will be 90 noticed that a perfect cubical package is formed which is very strong and very attractive for many purposes.

Of course the particular shape can be departed from; but I claim especially the construction of the blank and the manner of fastening the ends of it. 95

Having thus described my invention, what I claim as new, and desire to secure by Letters Patent, is—

1. As an improved article of manufacture, a folding box comprising five side portions, two of them to entirely overlap and cover the side at which they meet, said overlapping side flaps having slots in the opposite sides to lock them into one another, and a wing on each overlapping flap to fold and close the ends of the box.
2. As an improved article of manufacture, a folding box comprising five side portions, two of them to entirely overlap and cover the side at which they meet, said overlapping side flaps having slots in the opposite sides to lock

them into one another, a wing on opposite sides of the overlapping flaps, and short flaps on the opposite sides of the two sides at right angles to the overlapping flaps, said wings and short flaps being adapted to fold in and close the ends of the box.

In testimony whereof I have signed my name to this specification in the presence of two subscribing witnesses.

ZAIDA B. WEBB.

In presence of—

WARREN B. HUTCHINSON,
JOHN CAROLAN.
